UNITED STATES PATENT OFFICE.

VINCENZO SACCOME, OF JOHNSTOWN, PENNSYLVANIA.

TROLLEY-POLE HEAD.

1,417,945.

Specification of Letters Patent. Patented May 30, 1922.

Application filed January 10, 1922. Serial No. 528,211.

To all whom it may concern:

Be it known that I, VINCENZO SACCOME, a subject of the King of Italy, residing at Johnstown, in the county of Cambria and 5 State of Pennsylvania, have invented certain new and useful Improvements in Trolley-Pole Heads, of which the following is a specification.

The present invention relates to improvements in trolley pole heads and includes mechanism which will reduce to a minimum possibility of the trolley wheel leaving the wire.

A principal object of this invention is to 15 equip a trolley pole head with mechanism which will guide the trolley wheel back into engagement with the wire, if perchance the latter should be displaced, the mechanism being so constructed and arranged that it 20 will in no way interfere with the normal functioning of the trolley pole.

Another object of the invention is to so 25 construct the trolley head that its wheel and the guiding mechanism will be positively held in a predetermined position to insure effective operation of the device at all times.

Other objects of the invention will be in 30 part described and in part understood from the following description of the preferred form of the invention illustrated in the accompanying drawings wherein:

Fig. 1 is a side elevational view of a trolley head constructed in accordance with this invention illustrating its application;

Fig. 2 is a front elevational view of the same;

Fig. 3 is a vertical sectional view of the device;

Fig. 4 is a vertical sectional view taken on 40 the line 4-4 of Fig. 3 looking in the direction of the arrow;

Fig. 5 is a sectional view taken on the line 5-5 of Fig. 4;

Fig. 6 is a side elevational view of the 45 trolley head per se;

Fig. 7 is a sectional view of one of the 50 guide housings illustrating the manner of mounting the guide therein;

Fig. 8 is a detail enlarged sectional view 55 taken on the line 8-8 of Fig. 2 illustrating to advantage the manner of mounting one of the guide abutment blocks, and

Fig. 9 is a sectional view of a modified

form of guide housing showing a guide mounted therein.

In the drawings, in order to illustrate the application of this invention a portion of a trolley pole A is shown which may be of the usual or any desired configuration. The upper end of the trolley pole is equipped with a head 9 which preferably is detachably mounted on the pole and terminates in a forked upper end which embodies branches 10. Each of said branches is equipped with a spring pressed Y-shaped arm 10' the furcations of which are engaged with feet 11, said feet being formed on a washer 12. As illustrated to advantage in Fig. 5, the feet 11 are offset from the plane of the washer 12 and are carried directly within one of the branches 10 while the washer per se extends beyond the inner face of the branch. An axle 13 extends through the washers 12 and also through the branches 10 of the trolley head. The outer ends of the axle 13 are reduced and screw threaded, as indicated at 14, and project appreciably beyond the branches 10. The axle 13 carries a trolley wheel 15 which may be of the usual or any desired configuration. The hub of this wheel is embraced on both ends by the washers 12 thereby retaining the wheel centrally on the branches 10 and permitting the wheel to be flexed laterally in either direction for an obvious purpose.

Guide members are provided one of which is mounted upon each of the branches 10 of the head 9. Each of said guide members consists of a guide housing 16 which has a rib 17 formed on its inner face, the rib complementing the configuration of its branch 10 and being snugly engaged therewith to prevent relative movement between the branch and housing. Each housing is slidably mounted upon the reduced end 14 of the axle 13 and has a segmental recess 18 formed therein which receives one end of a guide 19. A guide 19 has an opening formed in its inner end which receives one of the reduced ends 14 of the axle, as shown in Fig. 7. The guide is normally held against one wall of the recess by the expansive action of a coil spring 20, one end of the latter being convoluted on an arcuate rod 21. This rod is provided with a screw threaded end which 100 engages the guide while the opposite end 105

projects through the recess 18 and into a semi-circular passage-way 22. The opposite end of the spring 20 extends into the passage way 22 and has its terminal convolution engaged with the end wall of the passage-way. Each guide has an abutment block 23 mounted on its inner face, the block having a groove extending longitudinally therethrough which receives a tongue 24 formed 10 on the inner face of the guide. Each block carries a bolt 25 the latter having a screw threaded shank which projects through a slot 25' formed in the guide. A thumb nut 26 is mounted upon the threaded shank of 15 the bolt. Preferably the inner face of each of the abutment blocks 23 is rounded and has its lower terminals in close proximity to the periphery of the wheel 15 to thereby facilitate engagement of the trolley wire 20 with the wheel. A portion of the lower end of each abutment block is extended to lie between the trolley wheel and the inner face of its housing 16. It is apparent that the abutment blocks 23 may be adjusted 25 when desired to take up wear, conform to different sizes of trolley wheels or to permit replacement should they be mutilated or otherwise rendered unsuitable for use.

In order to close the recess 18 and prevent the entrance of extraneous materials thereinto, a closure 27 is provided which has the opposite margins thereof flexed over and engaged with the opposite sides of the guide housing 16. A portion of the closure 27 is 30 struck upwardly to provide a lug 28 which is secured to the guide 19. Consequently, the closure will move in its entirety with the guide. However, the closure is of sufficient length to at all times insure complete 35 covering of the recess 18 immaterial of the position of the guide.

In use of this device it is apparent that the trolley head is engaged with the trolley wire in the usual manner by permitting the 40 guide members 16 to pass upwardly and straddle the trolley wire until the latter engages the wheel 15. In view of the arrangement of the guides 16, it will be apparent that accidental displacement of the 45 trolley wire will be reduced to a minimum. If the wheel is disengaged from the wire, there is little or no possibility of the trolley pole gravitating to a point where the wire would clear the upper terminals of the 50 guides. However, even should this condition exist reengagement of the wire will be greatly facilitated in an apparent manner. By permitting movement of the guides in 55 their housing, it will be appreciated that should an object contact therewith which is disposed at an angle to the path of movement of the trolley pole, the guides would be flexed rearwardly to permit the object to 60 pass thereover without mutilating the guide members or without in fact disengaging the 65

trolley pole from the wire. As soon as the object has been passed, the guides will be returned to their normal positions by the expansive action of the springs 20. It is apparent that construction of the device is 70 such that access may be gained to any part thereof conveniently and quickly so that repairs may be made thereto without undue delay. The mechanism may be made of wood, metal or other suitable material. 75

If desired, the trolley wire guides may be mounted so as to permit movement thereof in either direction thereby especially adapting the device for use on car lines where the car is not turned around at the terminal but 80 the trolley pole thereof merely reversed. This form of the invention is illustrated in Fig. 9 wherein a guide housing 16' is provided which has a recess 18' formed therein. This recess communicates with both ends of 85 a passageway 22'. A circular rod 21' is movable through the recess 18' and passageway 22' and has fixedly mounted thereon a guide 19'.

The guide 19' is of the same construction 90 and is mounted in the housing 16' in the same manner as the guide 19 is mounted in the housing 16. The rod 21' has a pair of springs 20' convoluted thereon one being arranged on each side of the guide 19'. These 95 springs engage an abutment 29 which is arranged transversely through the passageway 22' and is fixed to the housing 16'. Pressure on the guide 19' urges the rod 21' through the abutment 29 thereby compressing one of the springs 20' depending upon 100 the direction of movement of the guide. As soon as pressure is released from the guide the latter will be returned to its normal position by the expansive action of the compressed spring. 105

Various changes may be made in this device especially in the details of construction, proportion and arrangement of parts within the scope of the claims herewith appended. 110

What is claimed is:—

1. A trolley head including a forked member equipped with an axle carrying a wheel, the ends of said axle being extended beyond the sides of said forked member, trolley wire guide housings engaged over the branches of said forked member, and a guide member mounted in each housing and pivoted on one end of said axle. 115

2. A trolley head including a forked member equipped with resilient arms, an axle extended through the branches of the forked member and carrying a wheel, washers pressed by said arms into engagement with 120 said wheel, and guide members carried by the branches of said head to direct the trolley wire into engagement with said wheel. 125

3. A trolley head including a forked end the branches of which are equipped with 130

spring pressed washers, an axle arranged through said washers and branches, a wheel revolvably mounted on said axle and embraced by said washers, a guide housing 5 mounted on each of the branches of said head and equipped with a rib which embraces the branch to prevent relative movement between the housing and branch, a guide

pivottally mounted in each housing and equipped with rounded abutment blocks for 10 directing a trolley wire into engagement with said trolley wheel, and spring means to return said guides into a predetermined position pursuant to movement of the latter.

In testimony whereof I affix my seal.

VINCENZO SACCOME.
